UNITED STATES PATENT OFFICE.

CLARENCE A. STRACHOTA, OF CHICAGO, ILLINOIS, ASSIGNOR TO LIPTAK FIRE-BRICK ARCH COMPANY, OF CHICAGO, ILLINOIS.

FURNACE WALL.

Application filed December 20, 1924. Serial No. 757,176.

This invention relates to furnace walls or walls that are to be subjected to high temperatures, and, generally stated, the invention consists of the novel devices, combinations of parts and arrangements of devices hereinafter described and defined in the claims. Broadly, this invention relates to furnace walls of the type disclosed and broadly claimed in the Liptak Patent No. 1,463,046, of July 24, 1923. Moreover, the invention relates particularly to wall structures comprising what are termed "permanent outer walls and replaceable inner walls" and which latter are subject to intense heat so that they will burn out more rapidly than the outer walls and, hence, require frequent replacement in whole or in part. In the accompanying drawings, which illustrate the invention, like characters indicate like parts throughout the several views.

Referring to the drawings:

Fig. 1 is a perspective with some parts removed, illustrating a wall designed in accordance with this invention;

Fig. 2 is a view corresponding to Fig. 1, but with the outer wall stripped except for the channel-forming tiles or blocks;

Fig. 3 is a perspective of one of the anchor blocks of the outer wall;

Fig. 4 is a perspective showing one of the shelf-forming blocks;

Fig. 5 is a perspective showing one of the wedge or key blocks;

Fig. 6 is a perspective of one of the crown blocks or tiles of the replaceable inner wall;

Fig. 7 is a perspective showing one of the lower channel-forming anchor plates; and

Fig. 8 is a perspective showing one of the upper channel-forming anchor plates.

The numeral 16 indicates buckstays shown in the form of upright steel I-beams properly spaced at the exterior of the wall structure. The outer wall is preferably made up of horizontal belts of brick 17 and interposed

rows of large channel-shaped anchor blocks or boxes 18. These anchor blocks 18 are preferably of fire clay or highly refractory material, but the bricks 17 may and usually

will be common bricks, although they may, of course, be of fire bricks. The anchor blocks 18 are formed with large aligned channels that open at the inner sides thereof, and their lower flanges are formed with raised lock ledges 19, for a purpose that will presently appear.

For holding the anchor blocks 18 horizontally aligned and anchored to the buckstays 16, there are provided lower anchor plates 20 and upper anchor plates 21, both of which have vertically extended flanges placed against the inner flanges of the buckstays and rigidly but detachably secured thereto by nut-equipped bolts 22. By reference to Fig. 2, it will be noted that each buckstay laps a joint between the abutting ends of two anchor plates 20 and two anchor plates 21, and is bolted thereto so as to tie the aligned plates rigidly together in proper alignment. The anchor blocks 18 are placed directly on the lower anchor plates 20 and the latter, as shown, are provided with raised lock ribs 23 that engage lock grooves 24 in the bottoms of said blocks. The upper anchor plates 21 have downturned end flanges 25 that engage lock grooves 26 in the tops of the blocks 18. The blocks 18 can be slid to position on upper and lower plates already applied to buckstays, or they may be placed on the lower anchor plates and the upper anchor plates thereafter applied. In either case, the anchor blocks will be very securely held in position and anchored to the buckstays. By reference to Fig. 2, it will be noted that the anchor plates 20 and 21 are set in flush, respectively, with the bottoms and tops of the blocks 18.

The spaces between the horizontal rows of anchor blocks 18 or between the anchor plates 20 and 21 are filled in with the brick belts 17, which latter may be of any desired thickness but will usually be of much less thickness or width than the anchor blocks 18, so as to leave intervening air spaces.

The replaceable inner wall is made up chiefly of horizontal belts of fire bricks 27, horizontal rows or courses of shelf-forming

bricks 28, and preferably also, horizontal rows or courses of crowning blocks or tiles 29. The shelf-forming blocks 28 extend from the inner wall into the channels of the 5 anchor blocks 18, and on their under sides, they are formed with lock shoulders 28^a that interlock with the lock ledges or shoulders 19 of said blocks 18. Wedge or key blocks 30 are placed on the tops of the shelf-forming blocks 28 and forced into close engagement with the upper flanges of the anchor blocks. Thus, the shelf-forming blocks 28 are very securely anchored to and rigidly supported from the anchor blocks 18 and 10 are indirectly supported from the buckstays. This makes it feasible to use very thin brick belts 17 in the outer wall. The fire brick belts 27 are built directly on the shelf-forming blocks 28 and their weight is carried 15 through the blocks 28 and 18 and anchor plates 20 and 21 to the buckstays. Of course, in a structure where buckstays are not secured to the anchor blocks, the outer wall would have to be made up of intermediate brick belts of much greater width 20 or thickness than is shown in the drawings. In the structure illustrated in Figs. 1 to 8, inclusive, the wedge or key blocks 30 project considerably into the inner wall and, 25 hence, the layer in part formed thereby is completed by a row of bricks 30^a.

As a feature of the present invention, provision is made whereby each brick belt 27 is independently supported by its own row 30 of shelf-forming blocks and the several brick belts 27 are capable of independent expansion and contraction without transmitting the expanding force from the one belt to the other. This is accomplished by 35 leaving a clearance space between the top row of tiles or crowning blocks 29 and the overlying ends of the shelf-forming blocks 28, as shown at 31. The lower flanges of the anchor blocks 18 come against or very 40 close to the inner ends of the crowning blocks 29 and thus close the flame passage that might otherwise be formed by the gap 31. To further close this joint, however, the crown blocks 29 are shown as provided 45 with raised flanges 32 that lap with depending portions 28^b of shelf-forming blocks 28.

In the wall structure described, as clearly appears, large air passages are formed between the inner and outer walls. These air 55 spaces or passages protect the bricks of the outer wall from the intense heat and, moreover, they afford channels through which preheated air may be drawn into the furnace to support combustion when desired.

60 In the wall structure described, it is evident that the weight of the several brick belts of the inner wall is not accumulated on the lower belt but that each row of shelf-forming blocks supports its own load 65 and independently carries the same to the

outer wall or, as shown, to the buckstays of the outer wall. Some of the brick belts of the inner wall will be subjected to much higher heat temperature than others and, hence, will be caused to expand to a greater extent; and this, as is evident, is properly taken care of by the arrangement above described. 70

From the foregoing, it is evident that the wall structure described is capable of various modifications and rearrangements within the scope of the invention herein disclosed and claimed. 75

What I claim is:

1. A wall structure comprising an outer wall and an inner wall, said outer wall comprising refractory anchoring channels and intervening brick belts, and said inner wall comprising vertically spaced horizontal rows of shelf-forming blocks extended therefrom into the anchoring channels of said outer wall and supported thereby, and upper and lower anchor plates anchored, respectively, to the tops and bottoms of said refractory anchoring channels. 80

2. A wall structure comprising an outer wall and an inner wall, said outer wall comprising refractory anchoring channels and intervening brick belts, and said inner wall comprising vertically spaced horizontal rows of shelf-forming blocks extended therefrom into the anchoring channels of said outer wall and supported thereby, upper and lower anchor plates anchored, respectively, to the tops and bottoms of said refractory anchoring channels, and buckstays to which said upper and lower anchoring plates are rigidly secured. 85

3. A wall structure comprising an outer wall and an inner wall, said outer wall comprising refractory anchoring channels and intervening brick belts, and said inner wall comprising vertically spaced horizontal rows of shelf-forming blocks extended therefrom into the anchoring channels of said outer wall and supported thereby, upper and lower anchor plates anchored, respectively, to the tops and bottoms of said refractory anchoring channels, and buckstays to which said upper and lower anchoring plates are rigidly secured at their abutting ends, the said buckstays serving to tie the said anchor plates together at their abutting ends. 100

4. The structure defined in claim 1 in which the brick belts of the inner and outer walls are spaced to form air passages, and in which said anchoring channels extend substantially to said inner wall to separate the several horizontal air channels. 110

5. The structure defined in claim 1 in which the brick belts of the inner and outer walls are spaced to form air passages, and in which said anchoring channels extend substantially to said inner wall to separate the several horizontal air channels, the said 115

shelf-forming blocks and the top layer of the underlying belt of the inner wall being spaced to permit free vertical expansion.

6. The structure defined in claim 1 in which the brick belts of the inner and outer walls are spaced to form air passages, and in which said anchoring channels extend substantially to said inner wall to separate the several horizontal air channels, the said

shelf-forming blocks and the top layer of the underlying belt of the inner wall being spaced to permit free vertical expansion, the said shelf-forming blocks and the top layer of the underlying brick belt having vertically lapped joints. ¹⁰ ¹⁵

In testimony whereof I affix my signature.

CLARENCE A. STRACHOTA.
